CIRCUIT BREAKER

Winthrop M. Leeds, Pittsburgh, Pa., assignor to
Westinghouse Electric Corporation, East Pitts-
burgh, Pa., a corporation of Pennsylvania

Application June 25, 1946, Serial No. 679,086

17 Claims. (Cl. 200—82)

1

This invention relates to circuit interrupting equipments, and more particularly, to a circuit breaker operated by fluid under pressure.

In recent years circuit breakers have been designed for operation by fluid pressure or compressed air mechanisms, and have been successfully employed in modern power systems wherein speed of response of each circuit breaker to development of a fault condition in the circuit is of prime importance. Compressed air operated circuit breakers have been developed in a number of different types for various service conditions, one well known type being the so-called oil circuit breaker having contact means adapted to be moved to closed-circuit position by a piston operated by compressed air, and to open-circuit position under the force of a suitable spring or springs, upon tripping of a latch mechanism. Such a circuit breaker is illustrated and described in the application of James M. Cumming and R. C. Cunningham, Serial No. 410,686, filed September 13, 1941, now Patent No. 2,408,199, issued September 24, 1946, and assigned to the assignee of this invention.

In a circuit breaker of the type referred to above, it is necessary to provide an operating mechanism that is trip-free either mechanically or pneumatically, so that when closing the breaker against a fault, the contacts will be made ready immediately to open at substantially the same speed as during a normal trip-out operation. A mechanical trip-free linkage system can be used to couple the fluid-pressure actuated piston to the contact structure by means of which the contact structure can be released from the operating piston and quickly moved to the open circuit position. This mechanical linkage system, however, has the disadvantage that it is quite complicated and costly to manufacture.

It is also desirable in breakers of the foregoing type, to provide means for effecting high speed reclosing of the breaker after it has been tripped in response to a fault in the circuit and to obtain immediate reopening in the event the fault persists. Several such reclosures in rapid succession, may be provided for, before the mechanism is finally locked out in cases where the fault does not clear. In high speed reclosing, the operating mechanism on at least the first trip-out, must be void of trip-free action so that fluid pressure can be applied under the operating piston to stop the contacts before reaching full open circuit position. On the final trip-out the operating mechanism must be trip-free to prevent further attempts of reclosing in the event that the fault still persists. Mechanical operating mechanisms

2

have been devised which embody double latch schemes to effect two successive trip-outs but these structures also have the disadvantage of complexity and would not function if it is desired to make two or more quick reclosures in succession.

It has been found therefore, that for certain classes of service as above indicated, a pneumatically trip-free operating mechanism is preferable in that it is more flexible and simpler in principle of operation as well as being simple in construction. In its broadest aspect such a mechanism may provide means for quickly dumping fluid under pressure from the operating cylinder to enable the operating piston to move with the contact means freed from any fluid pressure opposing such movement. To this end, it has been the usual practice to equip the circuit breaker with an auxiliary control circuit means operative to effect energization of an electroresponsive dump valve simultaneously with energization of the usual electro-responsive tripping mechanism of the circuit breaker.

Experience has shown that this type of exhaust valve or dump valve is adequate for so-called pneumatic trip-free operation of a breaker employed in a 60-cycle service in which a satisfactory speed of parting of the contacts of the breaker may be as much as three to five cycles. Applicant proposes to design still faster fluid pressure operative circuit breakers, however, for service requiring a contact parting time of only one to two cycles, and has devised means for rendering the compressed air operative mechanism of such a breaker capable of even more rapid movement during a close-open cycle.

One object of my invention is to provide an improved fluid pressure operated circuit breaker having means for rapidly eliminating any force tending to oppose contact opening movement thereof in response to tripping of the breaker.

Another object of the invention is to provide a circuit breaker of the above type having means for quickly balancing the fluid pressures acting on opposite sides of the usual operating piston at a predetermined time of a close-open cycle of operation.

It is another object of the invention to provide a number of alternative forms of compressed air operative mechanisms for a circuit breaker, in which a dumping feature is combined with a new means for establishing an accelerating fluid pressure which facilitates the desired rapid circuit opening movement of the circuit breaker operating parts.

Other objects and advantages of the inven-

tion will appear in the following more detailed description thereof, when taken in connection with the accompanying drawings, in which:

Figure 1 is an elevational sectional view, diagrammatic in form of a compressed air circuit breaker operating mechanism adapted to be equipped with auxiliary control means embodying the invention.

Fig. 2 is a fragmentary sectional view taken substantially along the line II—II of Figure 1, and embodying the invention in one form thereof;

Fig. 3 is a sectional view taken substantially along the line III—III of the combined dump and accelerating valve device shown in Figure 2;

Figs. 4, 5 and 6 are fragmentary sectional views illustrating other forms of auxiliary control valve mechanisms constructed in accordance with the invention, all of which are adapted to be used in connection with the apparatus shown in Figure 1.

Figs. 7, 8, 9 and 10 represent curves of pressure as a function of time for different exhaust valve arrangements that may be applied to the operating cylinder.

Figs. 11, 12 and 13 are diagrammatic positional views showing the progressive operation of the valve mechanism shown in Fig. 3.

Referring to Figure 1 of the drawings, the circuit breaker operating mechanism therein illustrated constitutes a single pole unit of a fluid pressure operated circuit breaker, having features of construction similar to those embodied in the circuit breaker described in the aforementioned patent application. The apparatus is illustrated schematically as including a suitable frame structure (not shown) supporting stationary contact elements 5 in the power circuit to be controlled, a movable resilient contact element 6 cooperative therewith and secured to a rod 7, a cylinder 10 having mounted therein an operating piston or abutment 11, and a piston rod 12 operatively connected to the rod 7 through the medium of an operating rod 13 and a beam 14. The beam 14 is journaled on a stationary fulcrum pin 15 and is pivotally connected at opposite ends to the respective rods 7 and 13. A coil spring 17 is mounted in cooperative relationship with the movable contact element 6 for urging that element toward an open circuit position. The piston 11 is responsive to the pressure of air admitted to a high pressure chamber 20 in cylinder 10 for actuating the piston rod 12, beam 14 and rod 7 to move the contact element 6 into circuit closing engagement with the stationary contact elements 5, in opposition to the force exerted by opening spring 17. The lower face of the piston 11 is subject to the pressure of fluid in a low pressure chamber 21, which is adapted to be vented to atmosphere by way of a port 19 (see Fig. 2) as hereinafter explained.

For maintaining the circuit breaker elements just described in circuit closing position, the circuit breaker apparatus is further provided with a transversely disposed beam 22, one end of which is journaled on a pin 23 carried by a link 24 that is in turn pivotally connected to a pin 25 carried by the frame structure. The beam 22 is operatively connected by means of a pin 28 to the piston rod 12 at a point above the cylinder 10, and also carries, at the end opposite the pin 23, a roller 30 which is adapted to be engaged by a suitable latch mechanism, generally indicated at 31, for holding the beam 22 and the associated elements of the circuit breaker in the circuit closing position, as shown in Fig. 1.

The latch mechanism 31 may be of any suitable design and, as illustrated, comprises a main latch member 32 journaled on a stationary pin 33 secured to the frame structure, a release pawl 34 pivotally connected to the frame structure by means of a pin 35 for cooperation with the latch member 32, and an auxiliary latch member 36 adapted for cooperation with the pawl 34. The main latch member 32 has a surface 38 adapted for latching engagement with the roller 30, and an extension 49 adapted for interlocking engagement with a portion of the pawl 34 for resisting counterclockwise movement of the main latch member about pin 33 under the force tending to raise the end of the beam 22 carrying the roller, and thus tending to effect disengagement of the latch member 32 from the roller. For biasing the main latch member 32 in a clockwise direction, there is provided a spring 42, which is mounted in an aperture formed in a suitable lug on the frame structure.

For tripping the latch mechanism 31, there is provided an electroresponsive trip coil 44, which is adapted to be energized through the medium of a suitable trip control circuit (not shown) for causing upward movement of an armature carrying a plunger 45 that is operatively aligned with one end of the pawl 34. The pawl 34 is normally urged into the position shown in Fig. 1 by means of a spring 47, which is adapted to yield upon operation of the pawl by the trip plunger 45. The auxiliary latch member 36 is inoperative when the parts are positioned as shown in Fig. 1, but serves to hold the pawl 34 out of interfering engagement with latch member 32 when the beam 22 and other operating elements of the circuit breaker are in circuit opening position. A coil spring 49 is interposed between a recessed portion of the cylinder structure 10 and a lug 50 on the auxiliary latch 36, and acts to tilt the latter in a counterclockwise direction about pin 35, causing the lug 50 to carry the pawl 34 in the same direction, when the end of the beam 22 carrying roller 30 is swung upwardly during an opening operation of the circuit breaker. It will be understood that a lug 51 carried on the upper end of auxiliary latch 36 is adapted to be engaged by the free end of the beam 22, when that beam is moved to the circuit closing position as shown in Fig. 1. With the auxiliary latch member 36 thus held down, the spring 47 is permitted to maintain the pawl 34 in interlocking engagement with the main latch member 32.

A reservoir 60 is provided for storing a supply of fluid under pressure for operating the circuit breaker, the flow of fluid being controlled through the medium of a control valve mechanism 61. This control mechanism comprises a casing structure 63 secured in a suitable manner to the cylinder 10, and having formed therein a valve chamber 64 communicating with the reservoir 60 and also through a supply passage 65 with the piston chamber 20. Mounted in the valve chamber 64 is a valve element 67 having a stem 68 on the upper end of which is secured a collar 70. A coil spring 71 is interposed between the collar 70 and a shoulder formed on a valve seat member 72, for urging the valve element 67 into engagement with an annular seat surface 73 formed on the seat member. Slidably mounted in a bore 77 formed in the casing 63 is a piston 78, which is normally held in an inoperative position as shown in Fig. 1 by means of a coil spring 74, and which is engageable with stem 68

under pressure of fluid in the bore 77 for unseating the valve element 67.

A pilot valve mechanism is provided for controlling operation of the piston 78 and the valve element 67, comprising a valve element 80, which is operative to control communication from a passage 81 leading from the reservoir 60, to a passage 82 leading to the bore 77. The valve element 80 is normally biased into seated position as shown in Fig. 1 and is connected through the medium of a stem 85 to a discharge valve element 86 formed on the lower end of an armature 87 mounted within an electroresponsive magnet coil 89. The magnet coil 89 is suitably mounted on a portion of the casing structure 63 and is adapted to be energized by means of the usual auxiliary control circuit for the circuit breaker. It is not deemed necessary to illustrate this control circuit inasmuch as the details of such a circuit are well known in the art, one form thereof being disclosed, for example, in the aforementioned patent application of Cumming et al. It will be understood that upon energization of the magnet coil 89, the armature 87 is operated to effect unseating of the valve element 80 and seating of the discharge valve element 86, thus establishing communication from the reservoir 60 to the bore 77 containing the piston 78.

Apparatus shown in Figures 2 and 3

Figure 2 of the drawings is a sectional view of the cylinder 10 and related elements of the circuit breaker taken substantially at right angles to the sectional view of Fig. 1, and illustrates one form of auxiliary control valve mechanism which, according to the invention, constitutes a combined dump valve and accelerating valve device. This valve device is indicated generally by the reference character 100 and comprises a casing structure 101 bolted or otherwise secured to the cylinder 10 and having formed therein a longitudinally disposed bore 102, which at the plane of section shown in Fig. 2 communicates with the high pressure chamber 20 by way of a passageway or port 105 and with the low pressure chamber 21 by way of a passageway 106.

The sectional view of the control device valve 100 illustrated in Fig. 3 is taken substantially along the line 3—3 of Fig. 2, which is in turn a sectional view taken along the line 2—2 of Fig. 1. Referring to Fig. 3, the bore 102 has slidably mounted therein a piston valve element 110 for controlling communication between the passages 105 and 106, and a separate vent valve element 111, having a stem 112 operatively aligned with the piston valve element 110. The vent valve element 111 serves to control communication between an atmospheric exhaust port 113 and a port 114 communicating with the passage 105. The piston valve element 110 is provided with an extension terminating in a portion 115, which is also adapted to be brought into closing relation with the respective passages 105 and 106, and has a pressure face subject to pressure of fluid admitted to a chamber 117 formed in casing structure 101. A coil spring 119 is interposed between the piston valve element 110 and vent valve element 111 for urging these elements apart, as shown in the drawing, while a second and preferably stronger coil spring 120 is interposed between the vent valve element and an end wall 121 of the casing structure. The vent valve element 111 is thereby biased into the normal position illustrated, wherein communication

between ports 113 and 114 is cut off, while piston valve element 110 is positioned to close communication between passages 105 and 106. It will be noted that with the parts in the normal position as shown, the end of the stem 112 on vent valve element 111 is spaced from the adjacent surface of piston valve element 110, while the portion 115 of the latter is held in engagement with a stop shoulder 125 formed on the wall of the chamber 117.

For controlling the supply of fluid under pressure to chamber 117, there is provided pilot valve element 130, which is mounted in a valve chamber 131 communicating by way of a passage 132 with the passage 105. The pilot valve element 130 is normally biased into seated position as shown in Fig. 3 and is adapted to be unseated upon energization of a suitable electromagnet 133 for establishing communication from the valve chamber 131 through a passage 134 to the chamber 117. The flow area of the passage 134 may be determined by proper adjustment of a plug member 136 having a screw-threaded engagement in a bore formed in casing 101. If desired, the pilot valve mechanism may be provided with an additional vent valve portion (not shown) serving to insure venting of the chamber 117 when the valve element 130 is seated in the same way as the valve 86 vents chamber 77 of the supply valve mechanism 61 shown in Fig. 1.

The compressed air operating means of the circuit breaker, including the piston 11 and the associated elements already described, are operable to effect normal closing operations of the circuit breaker starting from a full open circuit position, and are also operable to effect a quick automatic reclosing operation of the breaker, wherein the reclosing movement is initiated in an intermediate point in the opening stroke of the breaker after the main circuit to be controlled has been interrupted. The control circuits for controlling the energization of the electromagnet 89 associated with the supply valve mechanism 61, and the trip magnet or coil 44 may be substantially the same as the control circuits disclosed in the aforementioned patent application, Serial No. 410,686. The electromagnet 133 is preferably connected in parallel with the trip magnet 44 in these control circuits, which have been omitted from the present disclosure in order to avoid undue complication of the drawings and description. It will be understood, however, that the trip coil 44 and the pilot valve electromagnet 133 are adapted to be energized in response to an overload or short circuit in the main circuit, which the circuit breaker is designed to protect.

In operation, while the circuit breaker equipment is disposed in its circuit closing position as shown in Figures 1 and 2, the beam 22 is held in a substantially horizontal position with the roller 30 in latched engagement with main latch member 32, so that the circuit breaker is held positively in the circuit closed position against any force tending to separate contact element 6 from contact elements 5.

In order to effect an opening operation of the circuit breaker, the magnet coil 44 is energized through the medium of the usual control circuit, as already explained, whereupon the plunger 45 is quickly raised to disengage the pawl 34 from the main latch member 32. Due to the relatively small area of contact between the inclined surface 38 of the main latch member and roller 30, the spring 42 is unable to resist the slight counterclockwise movement of the latch required to

release the beam 22, and the latter is consequently moved upwardly about pin 23, while rod 13, beam 14 and rod 7 are at the same time actuated by the spring 17 to effect disengagement of the contact element 6 from the contact elements 5. The piston 11 is carried upwardly during the upward movement of the piston rod 12 with the beam 22. It is assumed that the pressure initially existing in the piston chamber 20 is that of the atmosphere, by reason of a communication between the passage 65 and atmospheric exhaust port 76, which is normally uncovered by the piston element 78 when in its uppermost position, as shown.

As hereinbefore explained, the electromagnet 133, shown in Figures 2 and 3, is energized simultaneously with the energization of the trip magnet 44, in effecting the opening operation of the circuit breaker just described. Operation of the valve 130 by the electromagnet 133 at this time does not result in any functioning of the control valve device 100, however, since only atmospheric pressure exists in the piston chamber 20.

Assuming that the control circuit for the circuit breaker is now rendered effective by operation of the usual auxiliary reclosing means (not shown) to cause a closing operation, the resultant energization of the magnet coil 89 effects closure of exhaust valve element 86 and unseating of pilot valve element 80, so that fluid under pressure is admitted from the reservoir 60 to the bore 11. The piston 78 is then forced downwardly to unseat the supply valve element 67 whereupon fluid under pressure is supplied from the reservoir 60 through passage 65 to piston chamber 20. The circuit breaker piston 11 is thereby moved downwardly and, through the medium of rods 12 and 13, beam 14 and rod 7, effects movement of the contact element 6 into bridging relation with contact elements 5, closing the main circuit.

Referring to Figure 2, it will be observed that the port 19, formed in the wall of the cylinder 10, is so disposed as to permit fluid to be driven from the low pressure chamber 21 to the atmosphere during the initial downward movement of the piston 11. Just before the piston 11 reaches its lowermost position, however, it closes the port 19, so that a predetermined amount of fluid is bottled up in chamber 21 to cushion final movement of the piston. It will also be understood that fluid under pressure admitted to the piston chamber 20 is free to flow through passage 105 and passage 132 to the valve chamber 131 containing the normally closed valve element 130.

If the fault in the controlled or main circuit has not been removed at the time the automatic reclosure of the circuit breaker occurs, the trip coil 44 and electromagnet 133 are again energized, simultaneously with deenergization of the coil 89, thus initiating a reopening operation of the circuit breaker under the force exerted by the opening spring 17. According to my invention, the control valve device 100 now becomes effective for facilitating the desired opening operation of the circuit breaker with maximum speed by causing first a rapid equalization of the fluid pressures acting on opposite sides of the piston 11 and then dumping any remaining fluid under pressure from the piston chamber 20 to the atmosphere. This operation of the control valve device 100 will best be understood by reference to Fig. 3, it being apparent that upon energization of the electromagnet 133 and consequent unseating of the valve element 130, fluid under pressure flows from the piston chamber 20 through the passages 75

105 and 132 and past the open valve to the piston chamber 117, and acts against the portion 115 to force piston valve 110 to the left overcoming the spring 119.

During the first portion of its traverse, the piston valve 110 establishes communication between passage 105 and passage 106 (Fig. 11) to admit fluid under pressure from the piston chamber 20 to the low pressure chamber 21 on the opposite side of the piston 11, thereby quickly equalizing the pressures acting on the piston. Upon continued movement of the piston valve element 110 against the force of spring 119, the piston portion 115 thereof is brought into closing relation with the passage 106 (Fig. 12). At the same time the piston valve element engages the end of the stem 112 of the vent valve element 111, and carries that element slightly out of its normal position against the force of spring 120. This slight movement of the valve element is sufficient to admit fluid pressure from the high pressure chamber 20 to the area between the valve elements 110 and 111. Since, at this time, the chamber 117 has high pressure gas trapped therein, the valve element 110-115 cannot move toward the right and the valve element 111 is blasted to full open position (Fig. 13) by direct force of the high pressure gas exhausting from the high pressure chamber 20 through ports 114 and 113 to the atmosphere. The valve elements 111 and 110-115 are restored to their normal positions (Fig. 3) by the springs 119 and 120 when the pressure in the chamber 20 has been reduced to a predetermined value and the pressure has leaked from the chamber 117. The communication between passages 105 and 106 is thus cut off just before the piston chamber 20 is vented to the atmosphere by way of passage 105 and the ports 114 and 113. It will thus be seen that for a brief interval of time, the entrapped fluid under pressure in the low pressure chamber 21 is rendered effective to accelerate the piston 11 upwardly to assist the usual circuit breaker opening spring 17 (see Fig. 1) in effecting the desired opening operation. When piston 11 uncovers the exhaust port 19, of course, the fluid under pressure remaining in chamber 21 is also vented to the atmosphere.

From the foregoing it will be evident that the auxiliary control valve device 100 is constructed and arranged to effect a reopening operation of the circuit breaker apparatus with a speed and freedom from resistance not heretofore attained by use of constructions heretofore proposed. The principal features of construction of the control valve device rendering possible this desired result include the equalizing valve element 110, which is operated only momentarily to permit fluid to flow around the circuit breaker piston 11 to balance the opposing pressure acting thereon, and the separate vent valve element 111, which subsequently dumps air above the piston to atmosphere, allowing the fluid under pressure trapped under the piston to accelerate the opening operation of the circuit breaker.

Apparatus shown in Fig. 4

In Fig. 4 of the drawings the invention is illustrated in a different form comprising an auxiliary control valve device 100a, which may be associated with the cylinder 10 of a circuit breaker apparatus having the same construction as that illustrated in Fig. 1. The control valve device 100a comprises a casing 150 having a bore 151 in which is slidably mounted a valve piston 152, which is adapted to control communication

from the piston chamber 20 to the atmosphere by way of a passage 105a and an exhaust passage 153. The valve piston 152 is normally biased to its closed position, as shown in Fig. 4, by the force of a coil spring 156. A control electromagnet 133a and a pilot valve 130a operative thereby are provided for controlling the supply of fluid from the passage 105a to the upper face of the valve piston 152 in initiating the operation, as hereinafter explained. The circuit breaker operating piston 11a is in this case provided with normally closed valve means operative as the piston approaches its lowermost position to establish communication from the piston chamber 20 to the low pressure chamber 21 below the piston. This valve means may comprise a plurality of valve elements 160, each adapted to engage a suitable valve seat 161 and having a stem 162 extending downwardly through an opening 163 into operative alignment with the casing element closing the lower end of cylinder 10. A coil spring 164 is preferably associated with each of the valve elements 160 for biasing the element toward its seated position.

When fluid under pressure is supplied in the usual manner to the piston chamber 20 for effecting a closing operation of the circuit breaker apparatus, shown in Fig. 4, the piston 11a is moved downwardly, it being understood that at this time the valve elements 160 are maintained in their closed positions, while piston valve element 152 is also seated to prevent escape of fluid from the piston chamber by way of the passage 105a. Just before the piston reaches the end of its downward stroke, however, the stems 162 of the valve elements 160 are brought into engagement with the lower wall of the low pressure chamber 21, so that the valve elements 160 are unseated to permit flow of the fluid from the piston chamber 20 to the chamber 21. Thus, if the circuit breaker has been closed on a fault, consequent energization of the electromagnet 133a, together with the usual trip magnet, as hereinbefore explained, results in unseating of the pilot valve element 130a, and downward movement of the piston valve element 152 under the pressure of air thus supplied from the piston chamber 20, which is thereby vented to the atmosphere. The circuit breaker opening spring meanwhile begins to pull the piston rod 12 and piston 11a upwardly, and the valve elements 160 are then closed by the respective springs 164 in time to trap some of the fluid under pressure in the low pressure chamber 21 to provide a momentary accelerating force assisting in the initial upward movement of the piston, until the piston uncovers exhaust port 19.

Apparatus shown in Fig. 5

In Fig. 5 there is illustrated still another form of auxiliary control valve device, indicated generally by the reference character 100b, which may be substituted for the control valve device 100 shown in Fig. 2, for providing certain of the operative features of that device. As shown in Fig. 5, the control valve device 100b comprises a casing structure 170 suitably secured to the cylinder 10 of the circuit breaker apparatus. Formed in the casing structure 170 is a valve chamber or passage 171 communicating with the piston chamber 20 within cylinder 10, and containing a pilot valve element 172 operative by means of an electromagnet 133b, which is adapted to be connected in the usual trip control circuit for the circuit breaker.

The pilot valve 172 is adapted to control opera-

tion of a main piston valve element 175 which is normally urged toward seated position as shown by the force of a coil spring 176. The main valve piston 175 controls communication from the passage 171 to a passage 178, which communicates with the low pressure chamber 21 below the piston 11 of the circuit breaker.

In operation, assuming that the circuit breaker is closed upon a fault and that the usual tripping circuit is energized as hereinbefore explained, resultant energization of the electromagnet 133b effects opening of the pilot valve 172 during the initial upward movement of the piston 11 by the usual circuit breaker opening spring. Upon unseating of the pilot valve element 172 fluid under pressure supplied to the passage 177 acts on the inner face of the valve piston 175 to force that element to its open position, thereby establishing communication between the piston chamber 20 and the low pressure chamber 21 at the opposite side of piston 11. In this manner the fluid pressures acting on the piston 11 are substantially equalized in a shorter time than would be the case if the fluid under pressure in the piston chamber 20 were merely dumped to the atmosphere. It will be understood that the time required for equalization of the pressures above and below the piston can be minimized by suitably designing and proportioning the elements of the apparatus shown in Fig. 5 so that the volume of the low pressure chamber 21, while the piston 11 is in a lower position as shown, will be only a fraction or about ten to twenty percent of the volume of piston chamber 20. Tests have indicated contact parting times as short as 1½ cycles for a circuit breaker equipped with the equalizing control valve mechanism just described, as compared to usual contact parting times of approximately 2½ cycles required in the case of a breaker having an ordinary dump valve arrangement.

Apparatus shown in Fig. 6

According to the invention as disclosed in Fig. 6, an auxiliary control valve device 100c is provided for accelerating operation of the piston 11 in the course of an opening operation of the circuit breaker following closure thereof on a fault in the main line. Operation of the control valve device 100c is similar in principle to that of the control valve device 100b shown in Fig. 5. Instead of merely equalizing the fluid pressures above and below piston 11, however, the control valve device 100c is effective to accelerate the upward movement of the piston 11 under the force of fluid under pressure supplied from a high pressure source such as the main supply reservoir associated with the circuit breaker.

As shown in Fig. 6, the control valve device 100c comprises a casing structure 190 adapted to be secured to the cylinder 10 of the circuit breaker by suitable means, such as bolts, and supporting an electromagnet 133c, which, like the electromagnet 133 shown in Fig. 2, is connected in the usual trip control circuit of the circuit breaker apparatus. Slidably mounted in a suitable bore in the casing structure 190 is a valve piston 192, which is adapted to control venting of fluid under pressure from the piston chamber 20 by way of an exhaust passage 193. A coil spring 194 is interposed between a wall 195 formed within the casing structure and the valve piston 192 for urging the latter into its normal seated position, as shown in Fig. 6. The electromagnet 133c controls operation of a pilot valve element 198 which when unseated is effective to

supply fluid under pressure from the piston chamber 20 to a pressure surface of valve piston 192. Formed in the lowermost portion of the casing 190 is a valve chamber 200, which communicates by way of a pipe 201 with a suitable supply reservoir, such as the reservoir 60 shown in Fig. 1. Contained in the valve chamber 200 is a supply valve element 202 having an operating stem 203, which is slidably mounted in scaling relation in a bore in wall 195 and carries an end element 205 operatively aligned with the valve piston 192. The supply valve element 202 is arranged to control communication between the valve chamber 200 and a passage 207 leading to the low pressure chamber 21 of cylinder 10. For normally urging the supply valve element 202 into its seated position as shown in Fig. 6, a coil spring 209 is interposed between the wall 195 and the enlarged end element 205 of the stem 203.

In operation assuming that fluid under pressure is trapped in piston chamber 20 at the moment when the circuit breaker is tripped, following a closing operation on a fault, energization of the electromagnet 133c in the usual manner effects operation of pilot valve 198 to supply fluid under pressure to the pressure face of piston valve element 192, which is thereby forced downwardly in opposition to the force of spring 194 for venting fluid from chamber 20 to the atmosphere. At the same time the valve piston element 192 strikes the enlarged end element 205 of stem 203 and thus effects unseating of the supply valve element 202, so that fluid at main reservoir pressure is quickly supplied to the low pressure chamber 21 below circuit breaker piston 11. A positive upward force is thus exerted against the piston 11 to increase the speed with which the circuit breaker is operated to its circuit opening position. It will be apparent, of course, that the supply valve element 202 will become operative only when the circuit breaker is tripped while fluid under pressure is present in the piston chamber 20.

In order to show more clearly the advantages derived from the foregoing operating mechanism control arrangements, reference is made to the curves of Figs. 7 to 10 wherein pressure is shown as a function of time. In each instance the full lines represent the pressure above the piston 11 pushing down in a direction opposing movement of the piston to the open circuit position. The dashed lines of Figs. 8 to 10 represent pressure under the piston 11 pushing up to assist the accelerating spring 17 in moving the contacts to the open circuit position. The vertical arrows represent the net force at a given time during operation. The time interval ΔT represents the critical time required to reverse the operating piston and obtain contact separation following initiation of the opening phase of the operation.

More specifically, Fig. 7 represents the pressure conditions above the operating piston of a pneumatically trip-free operating mechanism of the prior art in which the trip-free action is obtained solely by the use of a high-speed exhaust or dump valve which permits the compressed fluid above the piston to exhaust to atmosphere when closing the breaker on a fault so as to enable reversal of the piston with the breaker contacts to the open circuit position. It is apparent that the retarding force on the piston decreases with the rate of decay of pressure above the piston.

In Fig. 8 pressure conditions are depicted in the arrangement of exhaust valve control as shown in Fig. 5 wherein the high pressure cham-

ber 20 is connected by way of passages 171 and 178 and valve 175 to the low pressure chamber 21 so as to balance the pressure on each side of the piston 11. It will be noted that the retarding impulse opposing the contact opening spring has been reduced to substantially zero by the end of the critical time ΔT .

The pressure conditions shown in Fig. 9 are generally typical of those existing in the arrangements shown in Figs. 2 to 4 in which a two step operation is employed, the first of which allows pressure from the high pressure chamber 20 to build up under the piston 11 in chamber 21, thereby at least partially equalizing the pressure on opposite sides of the piston and the second step which seals off the chamber 21 and at the same time opens chamber 20 to atmosphere so as to provide an accelerating impulse on the under side of the piston. An inspection of the curves in Fig. 9 reveals at once that the performance of the apparatus shown in Figs. 2 to 4 is superior to that of apparatus shown in Fig. 5 or the prior art in that the time ΔT actually includes an interval when fluid pressure is accelerating the piston 11 upward to assist accelerating spring 17 in opening the contacts.

The pressure conditions existing during close-open operation of the arrangement shown in Fig. 6 and illustrated in the curves of Fig. 10 are generally similar to those shown in Fig. 9 with the exception that the pressure above the piston 11 would decay more nearly as shown in Fig. 7. Also the pressure under the piston rises to a greater value in that it is supplied from the main reservoir 60 or other suitable source. In this instance the acceleration time interval during the time ΔT is further increased over that obtained with the structures of Figs. 2 to 4, thereby giving even greater assistance to the accelerating spring 17 in opening the breaker contacts.

From the foregoing it will now be apparent that the invention provides novel structural and operational features for a fluid pressure actuated circuit breaker contributing to the speed of response of the apparatus to a tripping impulse in the course of a close-open cycle of operation. The invention has been disclosed with reference to several forms of circuit breaker apparatus constructed and arranged in accordance therewith, but it is to be understood that various changes in the structural details and arrangement of parts may be made without departing from the essential principles of the invention. It is desired therefore that the language of the appended claims be given the broadest reasonable interpretation consistent with the state of the prior art.

Having now described my invention, what I claim as new and desire to secure by Letters Patent is:

1. In a circuit breaker operative by fluid under pressure and comprising relatively movable contact means, a cylinder, a piston in said cylinder for operating said contact means and control valve means operative to control supply and release of fluid under pressure to and from said cylinder in such a manner as to effect fast contact opening operation of the circuit breaker on a "close-open" duty cycle; the combination of auxiliary valve means controlling a communication for rapidly conducting fluid under pressure from one side of said piston to the other, and means for actuating said auxiliary valve means simultaneously with initiation of a fast contact opening operation.

2. In a circuit breaker having relatively movable contacts and fluid pressure operating mechanism arranged to effect fast contact opening operation of the circuit breaker on a "close-open" duty cycle including a movable abutment subject to opposing pressures of fluid in a high pressure chamber and in a normally vented low pressure chamber; the combination of valve means operative to supply and release fluid under pressure to and from said high pressure chamber in effecting normal contact closing and opening operations, other valve means biased to closed position and automatically operated to open position during the closing stroke of a close-open operation to vent fluid under pressure from said high pressure chamber and to supply fluid under pressure to said low pressure chamber for promoting high speed reverse movement of said abutment and rapid contact opening movement of the abutment during a "close-open" operation, and a venting port opened by said movable abutment during the opening stroke to vent said low pressure chamber to atmosphere.

3. In a circuit breaker having relatively movable contacts and fluid pressure operating mechanism arranged to effect fast contact opening operation of the circuit breaker on a "close-open" duty cycle including a spring-biased movable abutment subject to opposing pressures of fluid in a high pressure chamber and in a normally vented low pressure chamber, the combination of valve means operative to supply and release fluid under pressure to and from said high pressure chamber in effecting normal contact closing and opening operations, means comprising a communication for conducting fluid pressure from one side of said abutment to the other, auxiliary valve means operative to open said communication to balance the fluid pressures acting on said abutment for preventing retardation thereof on the contact opening stroke during a "close-open" operation, exhaust valve means operated by said auxiliary valve means to vent fluid pressure from said high pressure chamber, and an exhaust port uncovered by said movable abutment during an opening operation to vent fluid pressure from said low pressure chamber.

4. In a circuit breaker having relatively movable contacts and fluid pressure operating mechanism arranged to effect fast contact opening operation of the circuit breaker on a "close-open" duty cycle including a movable abutment biased toward a contact opening position and subject to opposing pressures of fluid in a high pressure chamber and in a normally vented low pressure chamber, the combination of valve means operative to supply and release fluid under pressure to and from said high pressure chamber in effecting normal contact closing and opening operations, auxiliary valve means controlling a communication bypassing said abutment and operative by fluid under pressure in said high pressure chamber to effect substantial equalization of fluid pressures on both sides of said abutment, and electroresponsive valve means operable on the opening stroke of a "close-open" cycle for admitting fluid pressure from said high pressure chamber to operate said auxiliary valve means.

5. In a fluid pressure operated circuit breaker having movable contact means, biasing means for biasing said contact means toward open-circuit position, a cylinder and a movable abutment therein normally responsive to an increase in the pressure of fluid in said cylinder on one side of the abutment for moving said contact means to

closed-circuit position, the combination therewith of auxiliary valve means controlling a communication for supplying fluid under pressure to said cylinder for suddenly increasing the pressure of fluid on the opposite side of said movable abutment to facilitate a circuit opening operation of the circuit breaker by said biasing means, said auxiliary valve means comprising a normally low pressure valve chamber, a main valve element disposed in said valve chamber and subject to pressure of fluid in said normally low pressure chamber, a spring normally holding said valve element seated, a pilot valve operable to admit fluid under pressure to said valve chamber for operating said valve element, and electroresponsive means for operating said pilot valve to open position.

6. In a fluid pressure operated circuit breaker having movable contact means biased toward open circuit position, a cylinder, a movable abutment operative in said cylinder for actuating said contact means, and control valve mechanism operative to open position to control supply and release of fluid under pressure to and from a chamber at one side of said abutment in effecting respective closing and opening operations of the circuit breaker, the combination therewith of auxiliary valve means controlling a communication for diverting fluid under pressure from said chamber at one side of the movable abutment to the chamber at the opposite side thereof, and electroresponsive means operable simultaneously with the closure of said control valve mechanism upon initiation of a contact opening operation to effect actuation of said auxiliary valve means to open said communication.

7. In a fluid pressure operated circuit breaker having movable contact means biased toward open circuit position, a cylinder, a movable abutment operative in said cylinder for actuating said contact means, and valve means for supplying fluid under pressure to a first chamber in said cylinder at one side of the abutment for effecting a circuit closing operation of said contact means and operative to release fluid under pressure therefrom in initiating a circuit opening operation, the combination therewith of auxiliary valve means comprising a first auxiliary valve controlling a communication for conducting fluid pressure from said first chamber to a second chamber on the other side of said abutment and operative by fluid pressure upon initiation of a circuit opening operation to establish communication from said first chamber to said second chamber at the opposite side of the abutment, a second auxiliary valve controlling a relatively large exhaust port and operable by said first auxiliary valve to vent fluid from the first mentioned chamber to the atmosphere and an electromagnetically operated pilot valve for admitting fluid pressure to operate said first auxiliary valve.

8. In a fluid pressure operated circuit breaker having movable contact means biased toward open circuit position, a cylinder, a movable abutment operative in said cylinder for actuating said contact means, and an electroresponsive control valve means adapted to be rendered operable at one time to supply fluid under pressure to a chamber in said cylinder at one side of the abutment for initiating a contact closing operation of the circuit breaker and at another time to vent fluid from said chamber for permitting a circuit opening operation thereof, the combination therewith of an auxiliary valve mechanism, comprising a first auxiliary valve means operative by

fluid pressure upon initiation of a contact opening operation to augment the discharge of fluid under pressure from said chamber at one side of the abutment, a second auxiliary valve means operable by said first auxiliary valve means for effecting momentary supply of fluid under pressure to the chamber at the opposite side of the abutment, and electroresponsive means operable upon initiation of a contact opening operation to admit fluid pressure to operate said first auxiliary valve means.

9. In a circuit breaker having relatively movable contacts and fluid pressure operating mechanism arranged to effect fast contact opening operation of the circuit breaker on a "close-open" duty cycle including a spring-biased movable abutment subject to opposing pressures of fluid in a high pressure chamber and in a low pressure chamber, the combination of valve means operative to supply and release fluid under pressure to and from said high pressure chamber in effecting normal contact closing and opening operations, and auxiliary valve means comprising a first auxiliary valve controlling a communication between said high and low pressure chambers and operative by fluid pressure upon initiation of a contact opening stroke of said abutment first to establish communication between said high and low pressure chambers and then to close said communication, and a second auxiliary valve controlling an exhaust port and operated by said first auxiliary valve when said first valve closes said communication to vent said high pressure chamber to the atmosphere.

10. In a circuit breaker having relatively movable contacts and fluid pressure operating mechanism arranged to effect fast contact opening operation of the circuit breaker on a "close-open" duty cycle including a spring-biased movable abutment subject to opposing pressures of fluid in a high pressure chamber and in a low pressure chamber, the combination of control valve means operative to supply and release fluid under pressure to and from said high pressure chamber in effecting normal contact closing and opening operations, means comprising a passage communicating said high and low pressure chambers, and auxiliary valve means operative first to balance the opposing fluid pressures acting on said abutment and then to vent fluid under pressure from said high pressure chamber, said auxiliary valve means comprising a cylinder, a first valve member disposed in said cylinder comprising spaced integral valve elements operable by fluid pressure to first open and then close said communication to effect a momentary flow of fluid pressure from said high pressure chamber to said low pressure chamber, means comprising a vent port, a vent valve disposed in said cylinder in spaced relation with said first valve member and normally closing said vent port, said first valve member when operated a predetermined distance engaging and operating said vent valve to open said vent port, and means operable to admit fluid to said cylinder to operate said auxiliary valve means.

11. In a circuit breaker having relatively movable contacts and fluid pressure operating mechanism arranged to effect fast contact opening operation of the circuit breaker on a "close-open" duty cycle including a cylinder and a spring-biased movable abutment subject to opposing pressures of fluid in a high pressure chamber and in a low pressure chamber, the combination of valve means operative to supply and release fluid under pressure to and from said high pressure

chamber in effecting normal contact closing and opening operations, auxiliary valve means operative to balance the fluid pressures acting on said abutment for preventing retardation thereof on the opening stroke during a "close-open" operation, said auxiliary valve means including a normally seated valve element mounted in said abutment and mechanically operable to open position by engagement with said cylinder to establish communication between said high and low pressure chambers only when said abutment reaches a predetermined position near the end of its contact closing stroke, and an exhaust port uncovered by said movable abutment after a predetermined movement in opening direction to vent fluid under pressure from said low pressure chamber.

12. In a circuit breaker having relatively movable contacts and fluid pressure operating mechanism arranged to effect fast contact opening operation of the circuit breaker on a "close-open" duty cycle including a spring-biased movable abutment subject to opposing pressures of fluid in a high pressure chamber and in a normally vented low pressure chamber, the combination of control valve means operative to supply and release fluid under pressure to and from said high pressure chamber in effecting normal contact closing and opening operations, an exhaust valve operable by fluid pressure in said high-pressure chamber to vent said high pressure chamber, electroresponsive means operable on the initiation of the opening stroke of a "close-open" operation to admit fluid pressure to said exhaust valve to effect opening of said exhaust valve, and an auxiliary valve disposed to be engaged and moved to open position by said exhaust valve when said exhaust valve moves to open position to admit fluid pressure to said low pressure chamber.

13. In a circuit breaker having relatively movable contacts and fluid pressure operating mechanism arranged to effect fast contact opening operation of the circuit breaker on a "close-open" duty cycle including a spring-biased movable abutment subject to opposing pressures of fluid in a high pressure chamber and in a low pressure chamber, the combination of control valve means operative to supply and release fluid under pressure to and from said high pressure chamber in effecting normal contact closing and opening operations, an exhaust valve operative by fluid pressure upon the initiation of the opening stroke of a "close-open" operation to vent said high pressure chamber, an auxiliary valve operable by said exhaust valve for admitting a momentary supply of fluid under pressure to said low pressure chamber, electroresponsive means operable upon initiation of an opening operation to admit fluid pressure to operate said exhaust valve, and an exhaust port opened by said abutment during an opening operation thereof to vent said momentary supply of fluid under pressure from said low pressure chamber.

14. In a circuit breaker having relatively movable contacts and fluid pressure operating mechanism arranged to effect fast contact opening operation of the circuit breaker on a "close-open" duty cycle including a spring-biased movable abutment subject to opposing pressures of fluid in a high pressure chamber and in a normally low pressure chamber, the combination of control valve means operative to open and closed positions to supply and vent fluid pressure to and from said high pressure chamber in effecting normal contact closing and opening operations, aux-

iliary valve means controlling a passage for supplying fluid under pressure to said normally low pressure chamber for suddenly increasing the pressure of fluid in said low pressure chamber to facilitate a fast circuit opening operation of the circuit breaker by said biasing means, electroresponsive means operative upon initiation of the opening operation of a close-open duty cycle for actuating said auxiliary valve to open position, and a venting port opened by said movable abutment during the opening stroke to vent said low pressure chamber to atmosphere.

15. In a circuit breaker having relatively movable contacts biased toward open-circuit position and fluid pressure operating mechanism arranged to facilitate fast contact opening operation of the circuit breaker on a "close-open" duty cycle including a movable abutment subject to opposing pressures of fluid in a high pressure chamber and in a normally vented low pressure chamber, the combination of valve means operative to supply and release fluid under pressure to and from said high pressure chamber in effecting normal contact closing and opening operations, an exhaust port for venting said high pressure chamber to atmosphere, a normally closed exhaust valve controlling said exhaust port, other valve means controlling a passage for supplying fluid under pressure to said low pressure chamber to suddenly increase the pressure of fluid in said low pressure chamber to facilitate a fast circuit opening operation of said circuit breaker, electroresponsive means operative simultaneously with the initiation of the opening stroke of a "close-open" operation to effect movement of said exhaust valve to open position to vent said high pressure chamber, and said exhaust valve engaging and actuating said other valve means to open position to supply fluid under pressure to said low pressure chamber.

16. In a fluid pressure operated circuit breaker having movable contact means, biasing means for biasing said contact means toward open-circuit position, a cylinder, and a movable abutment therein normally responsive to an increase in pressure of fluid in said cylinder on one side of said abutment for moving said contact means to closed-circuit position, the combination therewith of auxiliary valve means operative by fluid pressure on said one side of said abutment for controlling a passage for supplying fluid under pressure to said cylinder on the opposite side of said

abutment only on the opening stroke of a close-open operation for suddenly increasing the pressure of fluid on the opposite side of said movable abutment to facilitate a fast circuit opening operation of said circuit breaker by said biasing means, electroresponsive means operative upon initiation of a fast opening operation of said circuit breaker to admit fluid pressure to actuate said auxiliary valve means to open position, and a venting port normally closed by said movable abutment and opened by said abutment during an opening operation to vent said cylinder on the opposite side of said abutment to atmosphere.

17. In a circuit breaker having relatively movable contacts and fluid pressure operating mechanism arranged to effect a fast opening operation of the circuit breaker on a "close-open" duty cycle including a movable abutment subject to opposing pressure of fluid in a high pressure chamber and in a normally low pressure chamber, the combination of valve means operative to admit a closing charge of fluid under pressure to said high pressure chamber to effect a normal contact closing operation, auxiliary valve means responsive to said closing charge of fluid under pressure in said high pressure chamber and operable to admit a momentary charge of fluid under pressure to said low pressure chamber to effect high-speed reversal of movement of said abutment to thereby facilitate a fast opening operation of said contacts, and means operative simultaneously with the initiation of the opening stroke of a "close-open" operation to initiate opening of said auxiliary valve.
